Patent for Issue

John Lang.

Dec. 1386

Patent No. 1386

John Long, of Massillon, Ohio,
Letters Patent No. 21 Dated Feb. 19, 1861.

The schedule referred to in these Letters Patent and making part of the same.

To all whom it may concern,

Be it known that I, John Long, of Massillon, in the County of Stark, in the State of Ohio, have invented a new and original Design for Cooking Stoves, and I do hereby declare that the following is a full and exact description of the same, reference being had to the accompanying drawings, and to the letters of reference marked thereon,

My invention consists in certain shapes, figures, ornaments and mouldings, and the arrangement thereof for a design for Cooking Stoves.

Fig. 1. is a view in perspective.

Fig. 2. is an end view of the mouldings around the edge of front bottom.

Fig. 3. is an end view of the mouldings around the edges of the main and oven tops.

Fig. 4. is an end view of the oven doors as if cut in two.

Fig. 5. is an end view of the front doors and panels in oven front, as if cut in two.

Fig. 6. is a four pointed star.

Similar letters of reference indicate corresponding parts in the several figures.

A. is the front bottom, around the edge of which is an ogee moulding the hollow part upward, and a small hollow corn molding on top, the outer edge of which forms apart of said ogee moulding, as shown in Figs. 1 and 2. The edges of all the upright plates of the stove are ornamented with said hollow corn moulding, as shown in part of Fig. 1, and fully in Fig. 2.

B. is the main top around the edge of which is an ogee moulding the hollow part upward, as shown in Figs. 1 and 3.

C. is the oven front around the ends of which is an ogee moulding the hollow part inward, and three oblong and raised panels in upright position the edges of which are ornamented with ogee moulding, the hollow part outward as shown in Fig. 1, and 5. The edges of the front doors are ornamented in the same manner as panels in oven front C. as shown in Figs. 1 and 5. The end door also except that it is circular, as shown in Fig. 1.

D. is the oven top, around the edge of which is an ogee moulding the hollow part upward as shown in Figs. 1 and 3, and the front portion ornamented with a sheaf of wheat on the left, a plough, on the right, and a scroll above the plough, as shown in Fig. 1.

E. is the oven doors of oval form surrounded with ogee moulding, with a raised panel of oval form surrounded also with ogee moulding, as shown in Figs. 1 and 4.

F. is the side plates around the front ends of which is an ogee moulding as shown in Fig. 1. Fig. 6. is a four pointed star with a disk in the centre, each point is convex and ellipsoid with an edge of the shape around the same, as shown in Fig. 6. This star is placed in the centre of each door and panel.

3

Dec. 1386

in oven front C, as shown in Fig. 1, and one on the left side plate opposite end door in like manner, the shape of all the other plates are as represented in Fig. 1.

What I claim as my invention and desire to secure by Letters Patent is the combination and arrangement of the within described shapes, figures, ornaments and mouldings, in a Design for Corking Stoves, as represented in the drawings.

Witnesses.
